UNITED STATES PATENT OFFICE

REUBEN C. BAKER, OF COALINGA, CALIFORNIA, ASSIGNOR TO BAKER OIL TOOLS, INC., OF HUNTINGTON PARK, CALIFORNIA, A CORPORATION OF CALIFORNIA

WALKING BEAM SWIVEL

Application filed January 21, 1930. Serial No. 422,353.

This invention relates to apparatus to be used in connection with deep well equipment and more particularly pertains to an improved type of walking beam swivel.

5 In my co-pending applications entitled Pitman bearing, Ser. No. 423,352, filed Jan. 21, 1930, and Counterbalanced pitman, Ser. No. 422,355, filed Jan. 21, 1930, I have shown novel means for handling a counterweighted pitman. In these applications I have shown 10 a mechanism capable of supporting the counterweight and enabling the counterweighted pitman to be easily removed from the crank pin without disconnecting the 15 pitman from the walking beam. In order to accomplish this, the walking beam, which is supported at its center by a Samson post, must be capable of swinging in a horizontal plane. In common practice the walking beam 20 must be able to oscillate in a vertical plane to transmit the reciprocal motion of the pitman at its one end to the pump rods attached to its other end.

25 Therefore, it is the principal object of the present invention to provide an improved connection for a walking beam and Samson post which enables the walking beam to oscillate both in a vertical and a horizontal plane, which connection is capable of being secured 30 against horizontal movement if desired while the walking beam is being used in its pumping operation.

One form which the invention may assume 35 is exemplified in the following description and illustrated by way of example in the accompanying drawing, in which:

40 Fig. 1 is a side elevation part in section showing a preferred form of my invention and certain structural features thereof.

Fig. 2 is an end view of the same.

Fig. 3 is a plan view of the same.

45 Fig. 4 is a perspective view of an upper pivot plate which forms a part of this invention.

Fig. 5 is a similar view of a lower pivot plate.

50 Referring more particularly to the drawing and especially to Figs. 1 and 2, I show portions of a Samson post 10 and a walking beam 11. Fastened to opposite sides of the

Samson post 10 by means of suitable bolts 12 are a pair of plates 14. The plates 14 extend upwardly beyond the top of the Samson post and support a pair of trunnion bearings 15. Caps 16 are bolted to and form the upper halves of the bearings 15.

55 A pair of trunnions 17 are formed integrally with and extend from opposite sides of a lower bearing plate 18. The trunnions 17 are journaled in the bearings 15 so that the bearing plate 18 is free to rock or pivot about the axis of the trunnions.

60 An upper bearing plate 19 is fastened to the lower side of the walking beam 11 by means of suitable bolts extending through the holes 20 in the plate. The holes 20 are countersunk from the underside of the plate in order that the heads of the fastening bolts will be flush therewith.

65 A hole 21 is formed in the center of the lower bearing plate 18 and a hollow cylindrical boss 22 extends downwardly from the center of the upper bearing plate 19. When the plates are placed together the boss 22 extends into the hole 21 and provides an axis about which relative movement of the two plates in a horizontal plane is possible. A pintle 23 extends through the two plates and with the aid of a washer 24 and a nut prevents 70 separation of the plates.

75 The top surface of the plate 18 and the bottom surface of the plate 19 are machined so that their relative motion will be opposed by a minimum of frictional resistance.

80 It will be seen that by a connection of the character described the walking beam is permitted to oscillate in the usual manner by means of the trunnions 17 and to rotate upon the Samson post in the manner and for the reasons set forth in my co-pending applications hereinbefore referred to. Obviously, however, the oscillatory and the rotary movement are not in some instances desired at the same time, so I have provided means whereby the rotary movement may be prevented or permitted at will.

85 In Figs. 3 and 4 a pair of arcuate slots 25 are shown in the lower pivot plate 18. The arcuate slots 25 are common to the same circle, the center of which is also the center of the

100

plate 18. Holes 26 formed in the upper bearing plate 19 communicate with the slots 25 when the plates are placed together. Bolts 27 carried by the holes 26 in the upper plate extend through the slots 25 and are provided with nuts 28 at their ends.

In order to prevent rotary movement of the walking beam when it is being employed in its oscillating capacity, the nuts 28 are tightened upon the bolts 27 with the result that the pivot plates 18 and 19 are firmly pressed together and relative movement between them is prevented. When it is desired to rotate the walking beam, the nuts 28 are loosened whereby the upper plate 19 which is fastened to the walking beam is allowed to rotate upon the lower plate 18 carried by the Samson post.

It is neither necessary nor desirable that the walking beam rotate through a complete circle and the length of the slots 25 serve to limit its rotary motion. When the bolts 27 reach the ends of the slots 25 further motion is prevented.

It is obvious from the foregoing that I have provided a simple and durable connection for walking beams whereby both oscillatory and rotary movement of a walking beam may be permitted relative to the Samson post upon which it is supported.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. In combination with a well pumping rig including a walking beam and a Samson post, a pair of trunnion bearings supported by the Samson post, a trunnion journalled in said bearings and supporting a pivot plate, and a second pivot plate fastened to the walking beam and rotatably mounted on the first pivot plate.

2. In combination with a well pumping rig including a walking beam and a Samson post, a pair of trunnion bearings supported by the Samson post, a trunnion journalled in said bearings and supporting a pivot plate, a second pivot plate fastened to the walking beam and rotatably mounted on the first pivot plate, and means engaging the two pivot plates, said means being capable of preventing relative movement of the plates.

3. In combination with a well pumping rig including a walking beam and a Samson post, trunnion bearings on the Samson post, a trunnion supported in said bearings and supporting a pivot plate, a central downwardly extending hollow bearing member on said pivot plate, a second pivot plate fastened to the walking beam, a hollow trunnion on said sec-

ond pivot plate and journalled in said bearing member, and means carried by the hollow trunnion for securing said pivot plates against separation.
